INVENTOR
BY
Victor J. Evans
ATTORNEY

UNITED STATES PATENT OFFICE.

ANDRY GUST. SEA, OF CHICAGO, ILLINOIS.

WALL CONSTRUCTION.

Application filed June 4, 1921. Serial No. 474,900.

To all whom it may concern:

Be it known that I, ANDRY G. SEA, a subject of the King of Sweden, residing at Chicago, in the county of Cook and State 5 of Illinois, have invented new and useful Improvements in Wall Construction, of which the following is a specification.

This invention relates to building construction and more particularly to a wall 10 construction and an object of the invention is to provide an efficient and comparatively cheap wall structure, the major portion of which is composed of concrete thereby providing a strong, rigid, and durable wall 15 construction which will materially increase the longevity of the building structure in which it is incorporated.

Another object of the invention is to provide, in a wall structure, a concrete wall reinforced by suitable foraminous reinforcing material and arranged to brace and reinforce studs of the building of which the wall is a part, and also to water proof the portions of the studs which 20 are engaged by the concrete to prevent rotting or deterioration of the studs as well as to water or damp proof the inner 25 surface of the concrete wall.

Other objects of the invention will appear 30 in the following detailed description and in the accompanying drawing wherein:

Fig. 1 is a fragmentary side elevation, partly in section of the improved wall construction.

Fig. 2 is a cross section through the wall 35 structure.

Fig. 3 is a detail section showing a slight modification in the wall structure.

Referring more particularly to the drawing, the improved wall construction is built 40 about the studs 1 of the building of which the wall is to be a part, and includes concrete indicated at 2 of which the wall is formed and a foraminous metal reinforcement 3 45 which is attached to the outer edges of the studs 1. The reinforcement 3 may be woven steel wire, interlaced rods, or bars, or any approved type of metal reinforcement, such as used in concrete construction.

The concrete wall structure 2 extends inwardly of the outer edges of the studs 1, as 50 shown at 4 in Fig. 2 of the drawing, and encloses substantially the outer halves of the studs 1, thereby interlocking the studs and concrete to form a rigid wall structure. The 55 studs 1 have their surfaces which are en-

gaged by the concrete of the wall structure water-proofed by means of any well known water-proofing compound as indicated at 1' or if desired they may have a sheet of water- 60 proofing material as indicated at 5 in Fig. 3 of the drawing, mounted about the portions of the studs which are engaged by the concrete to prevent rotting or deterioration of the posts by contact with the concrete or 65 by action of moisture contained in the concrete. The inner edges of the studs 1 have laths or a lathing structure of any suitable type as indicated at 6 attached thereto to which the plaster 7 is attached. As shown in 70 Fig. 2 of the drawing air spaces 8 are provided between the inner wall of the wall structure, which is formed by the laths 6 and plaster 7 and the inner surface of the outer concrete wall 2. The outer surface of the 75 concrete outer wall 2 may have a coating 9 of stucco or any suitable material thereon to add to the appearance of the wall.

By interlocking the studs 1 in the outer concrete wall, a wall of relatively great 80 strength and rigidity is provided which has sufficient strength to support upper or super structure which may be mounted thereon.

The surface of the outer concrete wall, which faces the inner wall structure is 85 coated with a damp proofing compound as indicated at 2' to prevent moisture passing through the air spaces 8 into the wall structure and consequent cracking or warping of the inner wall structure.

Concrete is subject to swelling or expansion and contraction under varied weather conditions and to prevent cracking of the walls formed as above specified layers 90 of waterproof papers, such as tar paper or the like are embodied in the wall construction at spaced intervals as clearly shown in Fig. 2 of the drawing. The layers of waterproof paper are preferably formed of a plurality of folds folded one upon the other so as to 95 permit limited expansion and contraction of the walls without cracking.

It is, of course, to be understood that the invention may be constructed in various other manners and the parts associated in 100 different relation and, therefore, I do no desire to be limited in any manner except as set forth in the claims hereunto appended.

Having thus described my invention what I claim is:

1. A wall structure for buildings comprising a plurality of studs, a concrete wall

partially enclosing said studs; metal reinforcements in said concrete wall, and folded layers of waterproof paper embodied in the wall at spaced intervals.

5. 2. In a wall structure for building, a concrete wall and a plurality of folds of heavy waterproof paper embodied in said wall at spaced intervals.

3. In a wall construction, a plurality of 10 studs, a concrete wall at one edge of said studs and enclosing substantially one half of the studs for interlocking the studs and

concrete wall, an inner wall engaging the edges of the studs opposite from the edges enclosed by said concrete wall, said inner 15 wall being spaced from the concrete wall to provide air spaces between the studs, and a plurality of folds of waterproof paper embedded in said concrete wall at spaced intervals and engaging said studs and extending 20 transversely from the studs to the outer surface of the wall.

In testimony whereof I affix my signature.
ANDRY GUST. SEA.
